James H. McCool, INVENTOR
BY *Victor J. Evans*

ATTORNEY

UNITED STATES PATENT OFFICE.

JAMES H. McCOOL, OF ELLSWORTH, KANSAS.

ATTACHMENT FOR POOL TABLES.

1,427,691.

Specification of Letters Patent. Patented Aug. 29, 1922.

Application filed January 11, 1921. Serial No. 436,451.

To all whom it may concern:

Be it known that I, JAMES H. McCOOL, a citizen of the United States, residing at Ellsworth, in the county of Ellsworth and State of Kansas, have invented new and useful Improvements in Attachments for Pool Tables, of which the following is a specification.

This invention relates to improvements in pool tables and more particularly to an improvement upon the structures disclosed in my applications for patent upon racking-frames for pool tables, Serial No. 422,867 and for pool tables, Serial No. 422,865.

An object of the invention is to provide a simplified racking structure for use upon pool tables, by means of which the pool balls shot into the pockets are guided into a rack structure comprising individual compartments whereby the balls pocketed by each player are automatically racked separately from those pocketed by another player.

A further object of this invention is to provide, in a pool table attachment as specified, an elevator structure by means of which the pocketed balls may be guided into the desired compartment in the rack and also to provide a gate structure movable to release the balls and allow them to travel through a suitable guideway into a placing rack or basket.

A further object of this invention is to provide means for facilitating proper positioning of the elevator structure to guide the balls into proper space within the rack.

Other objects of the invention will appear in the following detailed description and in the accompanying drawings wherein:

Fig. 1 is a side elevation of the improved rack showing it applied to a part of a pool table.

Fig. 2 is a detailed vertical section through the rack taken on the line 2—2 of Fig. 1.

Fig. 3 is a detail section taken on the line 3—3 of Fig. 1.

Fig. 4 is a side elevation of the improved ball receiving and placing device.

Referring more particularly to the drawing the numeral 1 indicates a pool table which is constructed in accordance with the structures disclosed in my applications for patent upon pool tables Serial No. 422,865. In this particular construction of pool table the pockets are open at both ends and the balls pass therethrough upon suitable track

structure 2, which guides the balls to the receiving compartment 3 of the racking structure 4. As clearly shown in Fig. 1 of the drawing, the ends 5 and 6 of the rails 2 terminate, one upon each side of the mouth 60 of the compartment 3, so that the pool balls indicated at A, after traveling off the rails 2, fall into the compartment 3 upon the elevator structure 7. The elevator structure 7 is supported for vertical movement in the 65 compartment 3 and comprises a main body member 8 having a concave surface 9 for receiving the balls. A cable 10 is attached to the bail 11 of the elevator structure and passes upwardly over a suitable guide pulley 70 12, having its end, remote from the end which is connected to the bail 11, connected to a sliding block 14. The block 14 has a rail 15 formed thereon which rides in a suitable groove 16 in the table 1. A spring operated latch bolt 17 is carried by the sliding block 14 and has a knob 18 thereon to facilitate the withdrawal of its locking end 19 from the openings 20 in the pool table 1. The openings 20 are positioned proper distance apart for guiding the pool ball A from the compartment 3 into any one of the compartments 21 of the rack structure 4. The compartments 21 are formed in the rack structure 4 by longitudinally extending rails 85 or rods 22 which incline downwardly from the receiving ends of the compartments to their delivery ends as clearly shown in Fig. 1 of the drawing. A hinged end 23 is provided at the outlet ends of the compartments 90 21 and it swings upon its pivot 24 for releasing the balls A to permit them to pass out of the compartments 21 into a passage-way 25, downwardly through the passage-way 25 into a substantially horizontal passage-way 26 from which they roll into a retaining basket 27. A suitable rack 28 is carried by the rack structure 4 for supporting the basket 27 and this basket is of sufficient size to hold the fifteen balls used in playing 100 pocket billiards or pool. A reinforcing strip 29 is attached to one side of the basket 27 and it has an angle bar 30 attached thereto to which a spotting rack 31 of the usual triangular shape is attached. As clearly shown 105 in Fig. 5 of the drawing the triangular spotting rack 31 extends at right angles to the basket 27 and when it is desired to spot the balls A the basket is lifted by the rack 28 using the spotting rack 31 as a handle and 110

placed at approximate proper position on the pool table after which it is tilted to place the spotting rack 31 on the table during which movement the balls A will roll out of the basket 27 into the spotting rack 31 for proper positioning on the pool table 1.

To facilitate proper adjustment of the elevator 7, by means of the block 14, suitable indicia 32, which may be of different colors or have numbers or letters imprinted thereon, are positioned on the racking structure 4, one in alignment with each of the openings 20 and thus if the player will remember his particular color or number as presented by the indicia 32 the elevator 7 may be adjusted to run the balls A from the pockets of the table over the rails 5 and 6 into proper compartment 21.

It is, of course, to be understood that the invention may be constructed in various other manners and the parts associated in different relations and, therefore, I do not desire to be limited in any manner except as set forth in the claims hereunto appended.

Having thus described my invention what I claim is.

1. A ball racking attachment for pool tables comprising a plurality of compartments, an end compartment having communication with all of said first named compartments, and an elevator adjustable in said end compartment to guide balls into any one of said first named compartments, said first named compartments having ball supports therein inclining towards the outlet ends of the compartments, a hinged gate at the outlet ends of said compartments and adapted to normally restrain movement of balls out of the compartments.

2. A ball racking attachment for pool tables comprising a plurality of compartments, an end compartment having communication with all of said first named compartments, and an elevator adjustable in said end compartment to guide balls into any one of said first named compartments, said first named compartments having ball supports therein inclining towards the outlet ends of the compartments, a hinged gate at the outlet ends of said compartment and adapted to normally restrain movement of balls out of the compartments, an outlet end compartment communicating with said first named compartments, a receptacle supporting rack carried by said racking structure, said racking structure having a passageway therein adapted to convey balls from said outlet end compartment into a retainer upon said rack.

3. A ball racking attachment for pool tables comprising a plurality of compartments, an end compartment having communication with all of said first named compartments, and an elevator adjustable in said end compartment to guide balls into

any one of said first named compartments, a flexible member connected to said elevator, a guide block, said flexible member connected to said guide block, and means carried by said guide block for locking the block in adjusted positions for supporting said elevator in adjusted positions against accidental movement.

4. A ball racking attachment for pool tables comprising a plurality of compartments, an end compartment having communication with all of said first named compartments and an elevator adjustable in said end compartment to guide balls into any one of said first named compartments, said first named compartments having ball supports therein inclining towards the outlet ends of the compartments, a hinged gate at the outlet ends of said compartments and adapted to normally restrain movement of balls out of the compartments, a flexible member connected to said elevator, a guide block, and means carried by said guide block for locking the block in adjusted positions for supporting said elevator in adjusted positions against accidental movement.

5. A ball racking attachment for pool tables comprising a plurality of compartments, an end compartment having communication with all of said first named compartments, means to guide balls into any one of said first named compartments, means to normally restrain movement of balls out of said first named compartments, an outlet end compartment communicating with said first named compartments, a receptacle supporting rack carried by said racking structure, said racking structure having a passageway therein adapted to convey balls from said outlet end compartment into a retainer upon said rack.

6. A ball racking attachment for pool tables comprising a plurality of compartments, an end compartment having communication with all of said first named compartments, means to normally restrain movement of balls out of said first named compartments, an outlet end compartment communicating with said first named compartments, a receptacle supporting rack carried by said racking structure, said racking structure having a passageway therein adapted to convey balls from said outlet end compartment into a retainer upon said rack, said ball guiding means comprising an elevator, a flexible member connected to said elevator, a guide block, said flexible member connected to said guide block for locking the block in adjusted positions for supporting said elevator in adjusted positions.

7. A ball racking attachment for pool tables comprising a plurality of compartments, an end compartment having communication with all of said first named compartments, means to guide balls into any one

of said first named compartments, means to normally restrain movement of balls out of said first named compartments, an outlet end compartment communicating with said first 5 named compartments, a receptacle supporting rack carried by said racking structure, said racking structure having a passageway therein adapted to convey balls from said outlet end compartment into a retainer upon 10 said rack, said ball restraining means comprising a gate hingedly supported at one end

and adapted to close the outlets of said first named compartments.

8. A ball racking attachment for pool tables comprising a plurality of compartments, an elevator for guiding balls into said compartments, means for holding said elevator in adjusted positions and a hinged gate at the outlet of said compartments for controlling the outlet of balls therefrom. 15 20

In testimony whereof I affix my signature.
JAMES H. McCOOL.
